UNITED STATES PATENT OFFICE.

JOHN MURPHY, OF PHILADELPHIA, PENNSYLVANIA, ASSIGNOR TO
HIMSELF AND GEORGE W. CARR, OF SAME PLACE.

IMPROVEMENT IN SKIPPING-RODS.

Specification forming part of Letters Patent No. 140,298, dated June 24, 1873; application filed
April 11, 1873.

To all whom it may concern:

Be it known that I, JOHN MURPHY, of Philadelphia, Pennsylvania, have invented a Skipping-Rod, of which the following is a specification:

The object of my invention is to provide a cheap, light, and durable substitute for the ordinary skipping-rope; and this object I attain by the use of a light elastic rod of rattan, rendered flexible by the removal of the outer surface or "skin," and provided at its opposite ends, as illustrated in the perspective views, Figures 1 and 2, and enlarged section, Fig. 3, of the accompanying drawing, with suitable swiveled handles B, which enable the rod to be readily grasped and retained in the hands.

The rattan, instead of being used in its natural state, has the outer surface or skin removed, which gives it the desired flexibility without materially reducing its strength, the

stripped rod being of a circular sectional form, as shown in Fig. 3. The rod is swiveled.

I prefer to swivel the opposite ends of the rod to its handles B B, as shown in Fig. 3, so that the said handles may be grasped firmly by the hands, and the rod turn within the same.

I claim—

The within-described skipping-rod, composed of a strip of rattan with the skin removed, and having at each end a collar, x, adapted to a recess in the handle B, in which the strip can turn, all as set forth.

In testimony whereof I have signed my name to this specification in the presence of two subscribing witnesses.

JOHN MURPHY.
